UNITED STATES PATENT OFFICE.

JOHN C. MILLER, OF PHILADELPHIA, PENNSYLVANIA, ASSIGNOR OF ONE-HALF TO EDGAR S. ELDRIDGE, OF PHILADELPHIA, PENNSYLVANIA.

SHADE-ROLLER BRACKET.

SPECIFICATION forming part of Letters Patent No. 752,089, dated February 16, 1904.

Application filed April 11, 1903. Serial No. 152,236. (No model.)

To all whom it may concern:

Be it known that I, JOHN C. MILLER, a citizen of the United States, residing at Philadelphia, in the State of Pennsylvania, have invented a new and useful Shade-Roller Bracket, of which the following is a specification.

This invention is an improved construction of shade-roller bracket, the object being to provide a simple and inexpensive construction of bracket which can be connected to the window-frame without the use of screws or nails; and a still further object is to provide a bracket which can be arranged at the upper end of the guideway for the lower sash, so that the said bracket will not interfere in the least with inside blinds connected to the window-frame.

With these objects in view the invention consists in constructing a shade-roller bracket from a single piece of sheet metal, said bracket comprising a depending bracket-arm, the supporting-legs provided with means for engaging the window-frame, whereby the bracket is secured in place; and the invention consists also in providing a depending leg integral with the depending bracket-arm and supporting-legs, said depending leg having an inwardly-projecting foot-piece, against which the upper end of the lower sash is adapted to strike, said leg and foot-pieces limiting the upward movement of the lower sash, and thereby preventing said lower sash coming in contact with the shade-roller bracket.

The invention consists also in certain details of construction, hereinafter fully described, and pointed out in the claims.

In the drawings forming part of this specification, Figure 1 is a perspective view showing the practical application of my invention. Fig. 2 is a face view of the shade-roller bracket arranged in the window-frame, portions of said window-frame being shown in section. Fig. 3 is a detail perspective view of the shade-roller bracket disconnected from the window-frame. Fig. 4 is a vertical sectional view of said bracket, the central depending leg being shown partly in edge view. Fig. 5 is a plan view of the blank before being folded into the bracket illustrated in Fig. 3.

In practice I prefer to construct my im-

proved construction of shade-roller bracket 50 from a single piece of sheet metal, inasmuch as simplicity and cheapness of construction are two essential objects of the invention, and in so constructing the bracket I employ a bracket-arm A and the supporting-legs B, together with a central depending leg D. The bracket-arm A is folded upon the line A', so that the bracket-arm A will occupy a vertical position, and it will of course be understood that the brackets are made in pairs, 55 one bracket having a circular aperture to receive the round pintle of the shade-roller, while the other bracket is formed with the elongated socket to receive the flat spring-pintle carried at the opposite end of the shade-roller. 60 The legs B are bent upon the lines B', and the leg D is bent upon the line D', thereby making the top portion of the bracket flat, so that it will fit evenly in the upper end of the window-frame, as shown most clearly in Fig. 70 2. The legs B are curved outwardly, as shown, and at their curved or bowed portions are provided with triangular-shaped barbs C, the outer face C' of each being straight and the inner face C'' of each being inclined, as most 75 clearly shown in Fig. 3. The barbs C are bent at right angles to the legs B and can readily be forced into the guiding-beads of the window-frame, thereby securely fastening the bracket to the window-frame without the 80 use of screws or nails. The lower ends of the supporting-legs are bent slightly inwardly, so that they can be easily grasped whenever it is desired to remove the bracket from the window-frame. The inherent spring of the 85 supporting-leg serves to grip the barbs in engagement with the window-frame after said barbs have once been forced into the said frame. The central depending leg D rests parallel with the depending bracket-arm A 90 and extends downwardly to a point a short distance below the lower ends of the supporting-legs, and at its lower end the depending leg is formed with an inwardly-projecting foot-piece E, against which the upper end of the lower sash strikes when the said lower sash is raised to its full limit, the purpose of the foot and leg being to limit the upward 95

movement of the lower sash and prevent it coming in contact with the shade-roller bracket.

It will thus be seen that I provide a simple, 5 efficient, and inexpensive construction of shade-roller bracket which can be used in the manner heretofore described for the purposes set forth.

Having thus fully described my invention, 10 what I claim as new, and desire to secure by Letters Patent, is—

1. A device of the kind described comprising a depending arm, spring supporting side legs, a central depending leg in the rear of 15 the arm extending below the arm and a projecting foot carried by said leg.

2. A shade-roller bracket comprising a flat top portion, an arm depending from said top portion, said arm having an aperture therein, 20 legs depending from said top portion on each side of the arm, said legs being divergent and of spring metal, and means extending below

said legs and adapted to limit upward movement of a lower sash.

3. A shade-roller bracket comprising a depending bracket-arm, the spring supporting-legs provided with barbs, and the central depending leg having an inwardly-projecting foot-piece, substantially as described.

4. A shade-roller bracket formed of a single piece of sheet metal and comprising the depending bracket-arm, the spring supporting-legs provided with triangular-shaped barbs, the outer edges of said barbs being straight, and their inner edges inclined, and the central depending leg having an inwardly-projecting foot-piece at its lower end, said foot-piece being arranged below the lower ends of the supporting-legs, for the purpose set forth.

JOHN C. MILLER.
